UNITED STATES PATENT OFFICE.

WILLIAM SEATON, JR., OF ROSEBANK, NEW YORK; JEANNETTE NEILSON SEATON
ADMINISTRATRIX OF SAID WILLIAM SEATON, JR., DECEASED.

COAL AND ORE HANDLING MACHINERY, &c.

No. 902,839.

Specification of Letters Patent.

Patented Nov. 3, 1908.

Application filed May 31, 1907. Serial No. 376,704.

To all whom it may concern:

Be it known that I, WILLIAM SEATON, Jr., a citizen of the United States, residing in Rosebank, Staten Island, in the State of New York, have invented certain new and useful Improvements in Coal and Ore Handling Machinery, &c., of which the following is a specification, reference being had to the accompanying drawings, forming a part hereof.

10 Coal and ore hoisting machinery, as now commonly employed, comprises a truck arranged to travel upon a rigid boom, guide sheaves carried by the boom, a hoisting engine to raise and lower the load by a rope or 15 ropes passing through the guide sheaves on the truck and another engine to cause the truck to travel to and fro upon the boom for the purpose of moving the load from one point to another. In large plants, where 20 high speed in operation is desired, two operators are often employed, one for each engine. The speed of operation, even with two operators, is limited by reason of the danger of collision between the load and the 25 boom through over-hoisting. The booms are necessarily of somewhat heavy construction and if the load is rapidly hoisted too high, so that it strikes the boom, serious injury to the machinery is apt to result. In 30 consequence of this danger, cautious operators are apt to slow down too soon and the full advantages of the machinery, as to speed of operation, are not realized. Moreover, the booms, by reason of their necessary 35 construction, are not well adapted to act as struts and their practicable length is, therefore, quite limited. All of these disadvantages are incident to the use of single booms, arranged for use upon one side only 40 of the towers by which they are supported and still greater difficulties are encountered when such booms are arranged to work on both sides of the towers, and the resulting apparatus is quite expensive, cumbersome 45 and not easy to handle.

In accordance with the present invention the use of a rigid boom, and indeed of any track for the support of the sheave truck, is entirely dispensed with. The horizontal 50 movement of the sheave truck is effected, as in the old construction, by one engine, while the hoisting, lowering, filling and dumping are effected or controlled by another engine. As there is, however, no rigid track, there is 55 no danger of collision through over-hoisting

of the load. The truck itself is quite light and is not liable to be injured by contact with the bucket, especially as it yields upward readily and no breaking of ropes or other injury can follow from any such over-hoisting as is liable to occur. Furthermore, the danger of over-hoisting being removed the high speed of the hoisting mechanism is continued much nearer the point of stopping and the full advantages of such plant, in 60 65 point of speed, can therefore be realized.

The invention will be fully explained hereinafter with reference to the accompanying drawings in which, for purposes of illustration and explanation, the same is shown as 70 embodied in convenient and practical constructions.

In the drawings—Figure 1 is a view in elevation of a steeple tower equipped with the present improvements. Fig. 2 is a top view of the parts shown in Fig. 1. Fig. 3 is a detail view, partly broken out to save space and on a larger scale. Fig. 4 is a view in elevation of the engine for effecting the horizontal travel of the sheave truck, seen from 75 80 a point of view at right angles to that of Fig. 3.

In the embodiment of the invention illustrated in Figs. 1 and 2 there is shown a steeple tower *a* of ordinary construction, except 85 that it is adapted for use upon a curved track and also for transfer to a transverse track so that it can be used upon a wharf with a curved front or run to the interior or to either side of a wharf, thereby avoiding the necessity of two tower equipments for a single 90 wharf on either side of which loading or unloading is to be carried on.

Suitably mounted upon the tower are gaffs *d* which may be raised and lowered, as required, by ropes *d'* and stayed in position if necessary by suitable guys not shown, although in the embodiment of the invention illustrated in Figs. 1, 2 and 3, the gaffs *d* are 95 V-shaped and directly opposed so that lateral guys are unnecessary. Upon each gaff is supported a guide sheave *d''* over which runs the horizontal traverse rope *e*, passing directly through the tower. The ends of the rope are secured respectively to the sheave 100 truck *f*, while the bight of the rope, being led through suitable guide sheaves *e'*, is preferably given one or more turns about the drum 105 *g* of the horizontal traversing engine, so that the rotation of the drum in one direction or 110

the other will cause the truck f to move horizontally in one direction or the other between the ends of the two gaffs. This horizontal traverse rope is kept quite taut, in order to avoid lost motion as far as possible, and suitable take-up devices are provided, such as the turn buckles e^2 through which the ends of the rope are connected to the truck f . If under the particular conditions of use of the apparatus it is found desirable to have the traverse rope e secured positively to the drum g , the rope may be divided and its ends separately secured to the opposite ends of such drum. In such case each end of the rope is preferably secured adjustably to the drum, for convenience in taking up slack.

The hoisting rope or ropes h, i , run from the drums of the hoisting engine h', i' over guide sheaves h^2, i^2 , at the tower head and thence between guide sheaves f' on the truck f to the bucket k , these ropes being operated in the usual manner to effect the raising, lowering, filling and dumping of the bucket.

It will now be understood that the load being raised and lowered in the usual manner, the movement of the load in a horizontal direction is effected by the horizontal movement of the flying truck f which has no support other than the rope e which, actuated by the engine g , effects the horizontal traverse of the truck in one direction or the other between the extremities of the gaffs d . Furthermore, as will now be readily understood, the flying truck f yields readily upward and is itself so light that no injury follows from collision of

the bucket therewith. Considerable over-hoisting of the bucket might take place after collision with no other result than the lifting of the flying truck or trolley or a lifting of the booms to a stalling point. Under these conditions the operators are relieved of their natural fears and will carry out the function of the machinery at the highest possible speed.

Various other changes in details of construction and arrangement will readily suggest themselves according to the necessities of different conditions of use and it will be understood, therefore, that the invention is not restricted to the precise construction and arrangement shown and described herein.

I claim as my invention:

Machinery for handling coal, ore etc., comprising a vertical support, oppositely disposed gaffs carried thereby, guide sheaves at the extremities of said gaffs, a horizontal traverse rope passing over said sheaves, a flying trolley supported and moved horizontally by said horizontal traverse rope, a guide sheave carried by said support above the trolley, and a hoisting rope passing over said last named guide sheave and through said trolley to be moved horizontally therewith to one side or the other.

This specification signed and witnessed this 22nd day of May, A. D., 1907.

WILLIAM SEATON, JR.
